UNITED STATES PATENT OFFICE

106,053

DESIGN FOR A DISPENSER FOR TOOTH PASTE, SHAVING CREAM, AND THE LIKE

Garnet Adam Maguire, Saint John, New Brunswick, Canada

Application April 9, 1937, Serial No. 68,656

Term of patent 14 years

To all whom it may concern:

Be it known that I, Garnet Adam Maguire, a subject of the King of Great Britain, residing at 94 Prince William Street, in the city of Saint John, Province of New Brunswick, Dominion of Canada, have invented a new, original, and ornamental Design for a Dispenser for Tooth Paste, Shaving Cream, and the Like, of which the following is a specification, reference being had to the accompanying drawing forming part thereof.

In the drawing:—

Figure 2 is a perspective view of the side of the dispenser, and,

I claim:

The ornamental design for a dispenser for tooth paste, shaving cream, and the like, as shown.

GARNET ADAM MAGUIRE.
